ATTORNEY

UNITED STATES PATENT OFFICE

ELLIS B. ANDERSON, OF MEMPHIS, TENNESSEE

AUTOMOBILE HANDLING DEVICE

Application filed August 31, 1929. Serial No. 389,640.

This invention relates to an elevator for raising automobiles or other vehicles from a lower floor to higher floors. It has especial relation to a device for raising a plurality of automobiles at the same time and for positioning them at progressively different floors.

The objects of this invention are to provide means for raising a number of automobiles at the same time to different floor levels. A further object is to generally improve the design and construction of such a device.

The means by which the foregoing and other objects are accomplished and the manner of their accomplishment will readily be understood from the following specification on reference to the accompanying drawings, in which:

Fig. 1, is a sectional end elevation of a five story building showing four automobiles in position to be raised to the four upper floors and in dotted position showing these automobiles after raising.

Fig. 2, is a floor plan of the elevator end of the building, and of the elevator.

Fig. 3, is an enlarged side elevation of the elevator platform and support.

Fig. 4, is a similarly enlarged end elevation of the same parts.

Referring now to the drawings in which the various parts are indicated by numerals, 10 are the building walls; 11 is the main floor; and 12, 13, 14 and 15 are the second, third, fourth and fifth floors respectively. 16 are the basement walls, 17 the basement floor and 18 a narrow elongated pit in which a hydraulic cylinder 19 is disposed. This cylinder is provided adjacent its upper end with trunnions 20 which are journalled in 21. 22 are foundations on which these pedestals are supported. 23 is the ram or plunger. 24 are beams preferably of I shaped cross section which are disposed across the building. These beams are parallel to each other and are spaced apart pref-

erably adjacent the ends of elevator platforms 25, 26, 27 and 28 which are to be raised by them. Each of the beams is provided at one end with an upwardly curved extension 29 preferably also of I shaped cross section, which extensions are provided with bosses or bearings 30. These bearings are journalled on pins 31, which are carried by pedestals 32. The pedestals 32 are supported on suitable foundation piers 33, and are so disposed that the two pins carried thereby are in axial alignment.

Mounted on the top of the beams 24 and secured thereto, are upwardly extending A frames 34, four being shown. A similar set of similarly positioned frames is carried by each beam. At the apex of the A frames are pins 35, on which joists 36 are pivotally mounted, these joists being disposed longitudinally along the beams. A transversely opposite pair of joists thus carried, support the floor or platform of each elevator. These A shaped frames are designated in the claims as supports extending rigidly upward from the beams. Depending from each of the joists or from the platform adjacent the joists are A frames 37, which A frames lie along side the beams and serve as rigid members through which the horizontal position of the platforms may be maintained. Each of these latter A frames is pivotally connected at its apex, as by pins 38, to struts 39 which are disposed equal distances below the pin mountings 35 of the platform and which struts lie parallel to the top of the beams. At one end these struts are pivotally connected as by pins 40 to pedestals 41. The pins 40 lie in the vertical plane of the beam pins 31, although they are laterally offset in order that the struts may lie at the side of the beams. It will be seen that the hinge pins for each beam and corresponding strut and the corresponding pair of platform pins lie at the corners of a parallelogram with rigid sides, so that when the outer ends of the

beams are raised thus raising the platforms, each of these platforms will at all times be maintained in horizontal position, provided such conditions initially exist. The platform supports are spaced at such distance from the pins 31, that when one of them is brought level with the particular floor with which it co-operates, the remainder of the platforms will be level with their respective floors. 5 This condition will obtain when the distance from the pins 31 to the support pins 38 is proportioned to the distance of the floors vertically above the pin 38. Ordinarily the floors will be equal distances apart, in which 10 case the distance between platform pins will be equal.

The beams 24 are connected intermediate their ends and ordinarily adjacent the middle thereof by cross girders 42 which in turn 20 carry bearings 43 spaced apart. Disposed between these bearings is the upper end 44 of the ram 23 which is pivotally connected to them by a pin 45.

46 indicates diagrammatically a hydraulic 25 pump and 47 an electric motor for driving the same. 48 is an oil pipe from the pump through one of the trunnions 20 into the cylinder, and 49 a return pipe to an oil tank 50. 51 is a pipe from the oil tank to the pump. 30 52 is a control valve. The detail and operation of such parts being well known and not a part of the present invention, need not here be shown.

In using the device the beams are lowered 35 by the ram to a horizontal position, bringing all the elevator platforms level with the main floor. Any or all, of the platforms may then be loaded, as by the automobiles shown, and oil or other liquid forced by the pump into 40 the cylinder, causing the ram to raise the beams upward around their pin centers, and raising the elevator platforms 25, 26, 27 and 28 respectively to the second, third, fourth and fifth floors. During such movement the 45 struts 39 will maintain the platforms in horizontal position. It will of course be understood that platform 28 may be raised and stopped at any one of the four floors, that platform 27 may be stopped at any of three 50 floors, and platform 26 at either of two floors. 19A shown dotted, indicates the position to which the cylinder swings during the upward movement of the elevator. 23A indicates the extreme extended position of the 55 ram, and 24A the corresponding position of the beams. 25A, 26A, 27A, and 28A show the resulting positions of the elevator platforms and 39A the corresponding position of the struts. The platforms are lowered by 60 allowing the oil to return to the tank and the ram to descend.

Having described my invention, what I claim is:

1. An elevator, for a building having a 65 main floor and a plurality of elevated floors,

comprising a pair of parallel beams spaced apart, and normally disposed parallel to said main floor level, pivotal mountings, one for each of said beams, positioned in alignment at right angles to said beams at one end thereof, supports extending rigidly upward from each of said beams, there being one support on each beam for each of said elevated floors, said supports being spaced from said pivotal mountings at distances proportional to the distance of said floors above said mountings, platforms pivotally mounted, each on a transversely aligned pair 70

of supports, members secured to and extending rigidly downward from each of said platforms adjacent said beams, pivotal strut 75 mountings disposed below said beam mountings, struts disposed parallel with said beams and carried by said strut mountings, pins connecting said rigid members to said struts, a hydraulic cylinder disposed below said beams and pivotally supported, and a ram in 80 said cylinder, hingedly connected at its upper end to said beams intermediate their ends, whereby said beams may be pushed upward to raise said platforms, and said platforms will be maintained in level position.

2. An elevator, for a building having a main floor and a plurality of elevated floors, comprising a pair of parallel beams spaced apart, and normally disposed parallel to said main floor level, pivotal mountings one for 85 each of said beams positioned in alignment at right angles to said beams at one end thereof, supports extending rigidly upward from each of said beams, there being one support on each beam for each of said elevated floors, said supports being spaced from said pivotal mountings at distances proportional to the distance of said floors above 90

said mountings, platforms pivotally mounted, each on a transversely aligned pair of supports, members secured to and extending rigidly downward from each of said platforms adjacent said beams, pivotal strut 95 mountings disposed below said beam mountings, struts disposed parallel with said beams and carried by said strut mountings, pins connecting said rigid members to said struts, a hydraulic cylinder disposed below said beams and pivotally supported, and a ram in 100 said cylinder, hingedly connected at its upper end to said beams intermediate their ends, whereby said beams may be pushed upward to raise said platforms, and said platforms will be maintained in level position.

2. An elevator, for a building having a main floor and a plurality of elevated floors, comprising a pair of parallel beams spaced apart, and normally disposed parallel to said main floor level, pivotal mountings one for each of said beams positioned in alignment at right angles to said beams at one end thereof, supports extending rigidly upward from each of said beams, there being one support on each beam for each of said elevated floors, said supports being spaced from said pivotal mountings at distances proportional to the distance of said floors above 105

said mountings, platforms pivotally mounted, each on a transversely aligned pair of supports, members secured to and extending rigidly downward from each of said platforms adjacent said beams, means, pin connected to said members, for maintaining said platforms level, a hydraulic cylinder disposed below said beams and pivotally supported, and a ram mounted in said cylinder, 110 hingedly connected at its upper end to said beams intermediate their ends, whereby said beams may be pushed upward to raise said platforms, and said platforms will be maintained in level position.

3. An elevator, for a building having a main floor and a plurality of elevated floors, comprising a pair of parallel beams spaced apart, and normally disposed parallel to said main floor level, pivotal mountings one for each of said beams positioned in alignment at right angles to said beams at one end thereof, supports extending rigidly upward from 115

each of said beams, there being one support on each beam for each of said elevated floors, said supports being spaced from said pivotal mountings at distances proportional to the distance of said floors above 120

said mountings, platforms pivotally mounted, each on a transversely aligned pair of supports, members secured to and extending rigidly downward from each of said platforms adjacent said beams, means, pin connected to said members, for maintaining said platforms level, a hydraulic cylinder disposed below said beams and pivotally supported, and a ram mounted in said cylinder, 125 hingedly connected at its upper end to said beams intermediate their ends, whereby said beams may be pushed upward to raise said platforms, and said platforms will be maintained in level position.

3. An elevator, for a building having a main floor and a plurality of elevated floors, comprising a pair of parallel beams spaced apart, and normally disposed parallel to said main floor level, pivotal mountings one for each of said beams positioned in alignment at right angles to said beams at one end thereof, supports extending rigidly upward from 130

each of said beams, there being one support on each beam for each of said elevated floors,

5 said supports being spaced from said pivotal mountings at distances proportional to the distance of said floors above said mountings, platforms pivotally mounted, each on a transversely aligned pair of supports, means for maintaining said platforms in horizontal position, a hydraulic cylinder disposed below said beams and pivotally supported, and a plunger in said cylinder, hingedly connected 10 at its upper end to said beams, whereby said beams may be pushed upward to raise said platforms, and said platforms will be maintained in level position.

4. An elevator, comprising a pair of parallel beams, aligned pivotal mountings for one end of said beams, a horizontal platform pivotally supported by and above said beams, means intermediate the length of said beams for raising the free end of said 20 beams, and means for maintaining said platform in horizontal position.

5. An elevator, comprising a pair of parallel beams, aligned pivotal mountings for one end of said beams, a plurality of horizontal platforms pivotally supported by and above said beams, and spaced apart along said beams, means intermediate the length of said beams for raising the free end of said beams, and means for maintaining said 30 platforms in horizontal position.

6. An elevator, comprising a pair of parallel beams, aligned pivotal mountings for one end of said beams, horizontal platforms pivotally supported by and above said beams, and spaced apart along said beams, means for raising the free end of said beams, and means for maintaining said platforms in horizontal position.

7. An elevator, comprising a pair of parallel beams, aligned pivotal mountings for one end of said beams, a hydraulic cylinder disposed below said beams, a pivotal support for said cylinder adjacent the upper end thereof, a ram in said cylinder pivotally secured to said beams intermediate their ends, a platform pivotally supported by and above said beams and means for maintaining said platform in horizontal position.

8. An elevator, comprising a pair of parallel beams, aligned pivotal mountings for one end of said beams, a hydraulic cylinder disposed below said beams, a pivotal support for said cylinder adjacent the upper end thereof, a ram in said cylinder pivotally secured to said beams intermediate their ends, platforms pivotally supported by and above said beams and means for maintaining said platforms in horizontal position.

9. An elevator, comprising a pair of parallel beams, aligned pivotal mountings for one end of said beams, a hydraulic cylinder disposed below said beams, a pivotal support for said cylinder, a ram in said cylinder pivotally secured to said beams platforms pivotally supported by said beams and means for

maintaining said platforms in horizontal position.

10. An elevator for a building having a main floor, and a plurality of elevated floors, comprising a platform for each of said elevated floors, and means for raising said platforms simultaneously at speeds proportional to the height above said main floor of the floor served by each, whereby said platforms will simultaneously arrive at their respective floors.

In testimony whereof I hereunto affix my signature.
